(57) **CLAIM**

The ornamental design for a measuring device, as shown and described.

DESCRIPTION

FIG. 1 is a perspective view of the measuring device according to the present invention.

FIG. 2 is a front view of a measuring device depicted in FIG. 1.

FIG. 3 is a rear view of the measuring device depicted in FIG. 1.

FIG. 4 is a left side view of the measuring device depicted in FIG. 1.

FIG. 5 is a right side view of the measuring device depicted in FIG. 1.

FIG. 6 is a top view of the measuring device of FIG. 1; and, FIG. 7 is bottom view of the measuring device of FIG. 1.
